[57] CLAIM

The ornamental design for a combined camera and support unit for computer applications, as shown and described.

DESCRIPTION

FIG. 1 is a top, front and right side perspective view of a combined camera and support unit for computer applications with the support member in a fully assembled condition, showing our new design;

FIG. 2 is a reduced front elevational view with the support member in a folded condition;

FIG. 3 is a rear elevational view thereof;

FIG. 4 is a right side elevational view with the support member in a fully assembled condition;

FIG. 5 is a top plan view, with the lens housing in an alternate position;

FIG. 6 is a bottom plan view with the support member in a folded condition;

FIG. 7 is a left side elevational view thereof; and,

FIG. 8 is a right side elevational view thereof.
